(57) **CLAIM**

The ornamental design for a pendant light shade, as shown and described.

DESCRIPTION

FIG. 1 is a perspective view of the pendant light shade; FIG. 2 is a right-side elevation of the pendant light shade shown in FIG. 1

FIG. 3 is a left-side elevation of the pendant light shade shown in FIG. 1;

FIG. 4 is a front elevation of the pendant light shade shown in FIG. 1;

FIG. 5 is a rear elevation of the pendant light shade shown in FIG. 1;

FIG. 6 is a top plan view of the pendant light shade shown in FIG. 1; and,

FIG. 7 is a bottom plan view of the pendant light shade shown in FIG. 1.

The broken lines shown in the figures represent portions of the pendant light shade that form no part of the claimed design.

1 Claim, 6 Drawing Sheets
